US0D1006850S

(12) **United States Design Patent** (10) Patent No.: **US D1,006,850 S**
(45) Date of Patent: ** Dec. 5, 2023

(54) **TRANSFER ROBOT**

(71) Applicant: **KUKA ROBOTICS GUANGDONG CO., LTD.**, Foshan (CN)

(72) Inventors: **Jiaxing Wang**, Foshan (CN); **Sivakumar Thangavelu**, Foshan (CN); **Jiayin Jin**, Foshan (CN); **Liuhua Yan**, Foshan (CN); **Zhaowu Ruan**, Foshan (CN)

(73) Assignee: **KUKA ROBOTICS GUANGDONG CO., LTD.**, Foshan (CN)

(**) Term: **15 Years**

(21) Appl. No.: **35/514,588**

(22) Filed: **May 13, 2022**

(80) **Hague Agreement Data**

Int. Filing Date: **May 13, 2022**

Int. Reg. No.: **DM/221535**

Int. Reg. Date: **May 13, 2022**

Int. Reg. Pub. Date: **Jul. 1, 2022**

(30) **Foreign Application Priority Data**

Nov. 18, 2021 (CN) 202130758424.5

(51) **LOC (14) Cl.** **15-99**

(52) **U.S. Cl.**

USPC **D15/199**

(57) **CLAIM**

The ornamental design for a transfer robot, as shown and described.

DESCRIPTION

FIG. 1.1 is a front view of a transfer robot, showing our new design;

FIG. 1.2 is a back view thereof;

FIG. 1.3 is a left view thereof;

FIG. 1.4 is a right view thereof;

FIG. 1.5 is a top view thereof;

FIG. 1.6 is a bottom view thereof; and

FIG. 1.7 is a perspective view thereof.

FIG. 1.6 includes ghosting or blurred portions showing unclaimed subject matter that form no part of the claimed design.

1 Claim, 5 Drawing Sheets
